LOCK BOX

Curtis A. Graver, Lexington, Ky., assignor, by direct and
mesne assignments, to Guardian Lockers Incorporated,
a corporation of Delaware

Application February 17, 1950, Serial No. 144,699

5 Claims. (Cl. 194—54)

This invention relates generally to lock mechanisms, more particularly to a coin-operated lock assembly for lock boxes such as those provided in public buildings for the temporary storage of luggage.

A primary object of this invention is to provide a coin-operated lock assembly for the doors of lock boxes, so that the boxes can be used by patrons without extensive instructions and with a minimum of inconvenience, the mechanism including features whereby the patron is prevented from inadvertently locking the box before his luggage has been placed therein, the device including a hinged false floor which operates mechanism preventing the locking of the mechanism until such time as the false floor is weighed down by luggage placed thereon.

Another object of this invention, of equal importance, is the provision of means to prevent the patron from inadvertently turning the key of the lock and moving the lock into locked position before the door has been closed, this feature and the feature in the preceding object being calculated to increase the popularity of the lock box, since the patrons are prevented from improper operation thereof.

Another object of this invention is to provide a coin box assembly, particularly adapted for public baggage storage, although not limited to this particular use, and which is relatively proof against tampering or misuse.

Still another object of this invention is to provide such means for positively locking the doors of the boxes whenever a proper coin is inserted into the lock mechanism and the key is turned, while allowing easy opening of the boxes by use of a proper key, except when storage is due, the key being prevented from entering in this last instance, and it is a feature of this invention to provide simple means whereby the operator of the establishment, or the agent in the station of a transportation company wherein the lock boxes are used, may easily adjust the lock to the "storage due" position when the box has been occupied over a predetermined period of time.

Yet another object of this invention is to provide a coin-operated lock box assembly which is simple to operate, both from the point of view of the patron and the agent in charge of the lock boxes, which is relatively inexpensive and practicable to manufacture, which is safe and which will give generally efficient and durable service.

With these and other objects definitely in view, this invention resides in certain novel features of construction, combination and arrangement of elements and portions as will be hereinafter described in detail in the specification, particularly pointed out in the appended claims, and illustrated in the accompanying drawings which forms a material part of this application, and in which:

Figure 1 is a front elevational view of a portion of a lock box assembly, including portions of different boxes to show the general arrangement of the elements in this invention, the doors of the boxes being shown in closed position;

Figure 2 is a view similar to Figure 1 and showing the door of one of the boxes open and with luggage therein, and it will be noted that the false floor of the box is depressed by this luggage;

Figure 3 is another view in front elevation, showing the structure of Figure 1, in part, showing the position of the key when the luggage has been placed in the box, the door closed, and the key turned into locked position, and this figure also shows a coin being dropped from

2

the locking mechanism into the coin box at the time that the key is turned into the position shown in this figure;

Figure 4 is a vertical sectional view, taken on the line 4—4 in Figure 1 and looking in the direction of the arrows;

Figure 5 is a similar view, taken on the line 5—5 in Figure 1, the view being enlarged and showing the structure in greater detail;

Figure 6 is another vertical sectional view taken on the line 6—6 in Figure 5 and it should be noted that in Figures 5 and 6 the mechanism is shown in unlocked position;

Figures 7 and 8 are views corresponding generally to Figures 5 and 6 and showing the mechanism in locked positions;

Figure 9 is a fragmentary elevational view designed particularly to show the latch plate, the means for indicating that storage is due, and the counter;

Figure 10 is an enlarged fragmentary elevational view designed to show the arrangement of means to prevent the locked mechanism from being shifted into locking position, except when the door has been fully closed;

Figure 11 and Figure 12 show the counter in two positions, the Figure 11 being taken on the line 11—11 in Figure 6;

Figure 13 is a vertical transverse sectional view taken on the line 13—13 in Figure 2 and showing the coin box construction;

Figure 14 is a vertical sectional view taken on the line 14—14 in Figure 13;

Figures 15 and 16 are horizontal sectional views taken on the respective section lines in Figure 7, it being noted that the Figure 15 represents the structure as viewed from underneath the main lock mechanism, while Figure 16 is the same mechanism viewed from above;

Figure 17 is a vertical sectional view, portions being shown in elevation, of the key actuated lock;

Figure 18 is a vertical sectional view showing the mechanism for indicating that storage is due;

Figure 19 is an elevational view of a tool for operating the mechanism illustrated in Figure 18; and

Figure 20 is a view, in perspective, of the part herein-after referred to as the base plate.

Similar characters of reference designate similar or identical elements and portions throughout the specification and throughout the different views of the drawings.

Referring now to the drawings in detail, this invention includes a construction embodying a plurality of tiered boxes on upright members 22, these members functioning as supports for lock mechanism and doors for the boxes, the doors being all similar and represented in this disclosure by the door 24.

The upright members 22 are covered by face plates 26, such a face plate being fragmentarily illustrated in perspective in Figure 20.

The front plate 32 of a coin box generally indicated at 34 and shown in some detail in Figures 13 and 14 serves to hold the face plate 26 in position covering the lock mechanism associated with each door. By this means, the operator is enabled to enclose all the lock mechanisms associated with any particular upright member 22 by simply locking the coin box 34 in position with the base plates 26 held upwardly by the said front plate

32 of the coin box. When the base plate 26 is thus held upwardly, it is prevented from detachment from the upper member 22.

It is usually preferable that the face plate be divided into sections, one such section being indicated at 26a. The face plate 26, and the sections 26a when provided, will include pins 27, best shown in Figures 13, 14, and in dotted lines in Figure 5, to engage bayonet slots 26b in the upright members 22. The coin box 34 slides horizontally into the bottom of upright member 22 which is suitably recessed and the top of the coin box is formed with a hopper top 36 to guide coins into the coin box.

Opposing flanges 38 on the inner surface of the upright member 22 act as centering means for the coin box. A small lock, generally indicated at 40, is provided on the coin box, the key 42 for which is retained by the agent

in charge of the lock boxes. The lock 40 has a rotatable latch bolt 44 with terminal lugs 45 adapted to hook behind flanges 46 on the upright member 22, and stop pins 48 limit the movement of the latch bolt 44 in one direction.

The lock mechanism associated with each door is largely mounted upon an angle plate 50 which is mounted upon the upright member 22, in a recess provided in the member by eccentric buttons having slots to receive a tool and abutment plates 53, best shown in Figures 5 and 7. The latch bolt 52 is vertically slidably mounted upon the angle plate 50 and this latch bolt has an elongated portion 54 extending upwardly for coaction with what will be referred to simply as the lock 56. This lock 56 is operated by a key 58 which is exposed at the front of the face plate 26 so that the patron may turn this key during the operation of the device. A key aperture 60 is provided in said face plate 26 and the lock mechanism includes a tooth 62 turned when the key 58 is turned and engageable in the slot 64 of the elongated portion 54 of the latch bolt, it being important for the understanding of this invention to note that the latch bolt is forced downwardly by the action of the key 58. The latch bolt 52 has another extending portion 66 adapted to frictionally engage a flange 68 which is spaced from the portion of the latch bolt actually engaging the latch plate 70 of the door, so that the latch bolt is well guided and prevented from being forced out of position by rough usage.

The latch plate 70 on the door is clearly illustrated in Figures 8 and 10, as well as in other figures of the drawings, and it should be here noted that special means is provided according to this invention to prevent the shifting of the lock mechanism to locking position before the door 24 is closed. A trigger 72 is pivoted on the upright member 22, as illustrated best in Figure 10, and is biased by a spring 74 into a position extending into a slot 222 in the upright, or jamb 22, illustrated in Figure 6 to hold the latch bolt 52 against moving into latch plate engaging position as shown in Figure 8 and in Figure 10, until such time as the door has been closed and the trigger 72 pushed into the position shown in Figure 10. In other words, the latch plate 70 engages the trigger 72, pushing the same against the action of the spring 74 into the position shown in Figure 10 when the door is closed, thus releasing the latch bolt 52 which falls into the latching position shown in Figure 10, when the key 58 is turned so as to make the tooth 62 engage the latch bolt and force the same downwardly.

When the coin has been pushed in, it will engage roller 90 releasing tooth 82 from lug 84 attached to the latch bolt 52. The vacant (unlocked) position of the pawl 76 is with the tooth 82 engaging the stop element 84. The weight of latch bolt 52 aided by spring 118, attached to latch bolt 52 and other suitable structure in the lock mechanism as shown in Figure 6, will start the downward travel of the latch bolt containing the coin in slot 94 in the latch bolt. The lock 56 is free to rotate through a portion of its operative arc even before the coin is completely inserted and this permits the start of movement of the latch bolt. Movement of the latch bolt 52 may be prevented by the latch bolt bearing on the trigger 72 if the door 24 is not closed or, normally, by the tooth 62 of the lock 56 engaging the slot 64 and by the lock 56 not being free for complete rotation without positive rotation thereof by the key 58 when the door is closed, whichever action first occurs. The pin 96 extends across the slot 94 and a small roller 98 may be mounted on this pin in the slot 94, as best illustrated in Figure 7, the coin being retained in slot 94 by coaction of roller 98 and a flange portion 92 of the pawl 76. Downward travel of latch bolt 52 also causes a plate 166, attached to latch bolt 52, to close coin-receiving slot 88 in the face plate. It should be noted that coin slot 88 is closed before lug 102 engages upper end portion 100 of the pawl 76.

The upper end portion 100 of the pawl 76 is engageable by the lug 102 in the lock 56 and is shifted when the key 58 is turned. This portion 100 of the pawl prevents the turning of the key and lock from unlocked position into the full locking position until such time as the coin 86 has been inserted and has moved the pawl 76 from the position illustrated in Figures 5 and 6 into the position which may be referred to as the coin-accepting posi-

tion shown in dotted lines in Figure 7 at 103. The portion 100 of the pawl 76 serves as a stop if the pawl 76 is tripped to release the tooth 82 from the element 84 by an article such as a finger nail file and where the lower end of the pawl 76 is not moved far enough to move the upper end of the pawl clear of blocking engagement with the lug 102. In this coin-accepting position, the upper end of the pawl 76 no longer acts as a stop to prevent the turning of the key and the lug 102 functions as a cam to shift the pawl from the coin-accepting position 103 into the coin releasing position indicated in full lines in Figure 7 and in Figure 8. When the pawl 76 is in coin engaging, or coin releasing position, the latch bolt 52 is free to be moved into latch plate engaging position, and such movement of the latch bolt carries the coin 86 down in the slot 94 under the flange 92 to release the coin, and insure that the pawl 76 is in its coin releasing position. It should be carefully noted that when the pawl 76 is positioned as shown in full lines in Fig. 7, the tooth 62 can force the latch bolt 52 downwardly into a position engaging the latch plate 72 as already described. Fig. 8 shows the position of the latch bolt 52 after such movement has occurred, and the latch bolt 52 engages the latch plate. The construction of the lock 56 will be referred to in greater detail hereinafter.

Means is provided to prevent the locking of the door until such time as luggage indicated at 106 in Figure 2 has been placed in the box. This means includes a hinged false floor 108, preferably hinged at the back of the box and depressible from the position shown in full lines in Figure 6 to the position shown in dotted lines in the same figure, against the action of a spring 110. An angle bar 112 is carried by the false floor 108 and is guided by barrel brackets 114 so that an upwardly extending end portion 116 engages the flanged portion 92 at the lower end of the pawl 76 preventing movement of the pawl from the said coin-accepting position to the position allowing the movement of the lock mechanism into door-locking position. The placing of luggage 106 on the false floor 108 depresses the floor so as to cause the upper end portion 116 of the bar 112 to move into the position indicated at 117 in Figure 6, thus releasing the lock mechanism. It will be clear that a patron will be prevented from inadvertently locking the door before placing the luggage into the lock box, since he cannot lock the door until such time as the luggage has been so placed. This will also help to discourage a practice of pranksters who deposit a coin and remove the key, keeping or disposing of the key without having placed anything in storage, this incurring the expense of replacing the key and changing the lock. Means is provided for counting coins deposited in the device. This means comprises a counter, generally indicated at 120.

The counter 120 will consist of a short lever 122 rigidly secured to the actuating shaft of the counter indicated at 124, the lever 122 being biased against rotation in one direction by a spring 126 secured to the lever at 128. The pin 96 carried by the lower end portion of the downwardly extending part of the latch bolt 52 engages and operates the lever 122 each time the latch bolt is moved into door-locking position. It is preferred that positive return of the lever 122 to the position indicated in Figure 11 will be assured by arranging the lever 122 so that the pin 96 engages a portion of the lever as the pin moves upwardly in order to assure that the lever will spring back under the influence of the spring 126.

The lock 56 includes a member 130 which is spring-biased by a spring 132 into a position such that a pin 134 carried by the member 130 is engaged in locking relation in a recess 136 in a barrel member 138 of the lock. The key 58 operates conventional lock mechanism to release the member 130 for such movement relative to the barrel 138. The spring 132 also serves to eject the member 130 and the barrel 138 from the casing 139 of the lock, when the pin 140 is retracted from engagement with the barrel 138 by means of a tool wedged between the casing and the head of the pin 140 by an operator seeking to change the lock. The locks can be changed by the operator in this manner without difficulty, since access to the pin 140 is facilitated by the mere removal of the face plate 26. A spring 142 engaging the pin 140 at one end and secured at the other end by a headed screw 144 normally retains the pin 140 in the position indicated in Figure 17. The above referred to lug 102 is carried by a strap 146 which is, in turn, secured to the member 130 by a screw 148, so that

the turning of the key 58 also turns the lug 102 for actuation of the pawl 76. Of course, the tooth 62 is likewise operated in the same manner, the mounting of this tooth being best illustrated in Figure 16.

Means to indicated the fact that a box has been held over an allowed period of time is provided in the form of a barrel casing 150 welded or otherwise secured to the angle plate 22 as best shown in Figure 18, together with an internally threaded sleeve 152 arranged coaxially thereof and having a set screw 154 which tightens to lock the sleeve 152 in the casing 150 when the sleeve is turned in one direction, the sleeve extending exteriorly of the angle plate 22 and having an adjustable flag 156 with a notice "Storage Due" visible in the key slot 60 when the flag is in one position. It is to be noted that the flag 156 prevents insertion of a jimmy or key into the lock 56 when the flag is positioned to close the key slot. The construction described immediately above prevents unauthorized adjustment of the flag 156, but an authorized agent will use a screwdriver 158, illustrated in Figure 19, to engage a slot 160 in the set screw 154, this screwdriver having a sleeve 162 with pins 164 to engage and hold the sleeve 152 while the set screw is backed off or tightened. Since the flag is fixed to the sleeve 152, the sleeve 162 is used to rotate the flag into the key slot or into hidden position.

The latch bolt 52 carries a plate 166 positioned to slide vertically inside the face plate 26 and notices "In Use" and "Vacant" are applied in any suitable manner on the face of the plate 166 so as to be selectively visible through a window 168 in the face plate, according to the positioning of the latch bolt in locked or unlocked position, respectively.

The operation of this invention has already been described in the above specification of the mechanical details of the device, and further description would appear to be unnecessary.

It might be added, however, that when luggage has been placed in the box and the door closed, the key can be turned to lock the door and the key can then be removed from the lock and retained by the patron until he desires to retrieve his luggage.

Having described the invention, what is claimed as new is:

1. In a lock box assembly, a lock box having an access door and a door jamb, a key-operated lock unit mounted on the jamb, a door-locking latch mechanism mounted on the jamb and including a latch bolt, a co-acting latch plate on the door, an elongated portion of said latch bolt being slidably supported on the jamb and operatively connected with said lock unit for actuation by the lock unit, a pawl pivoted on the jamb and in one position engaging said latch bolt to prevent the latch bolt from moving into latch plate engaging position, said door jamb having a coin slot leading to said pawl, said pawl being adjacent said door jamb slot and being positively shifted from said one position to a coin-accepting and latch bolt releasing position by a coin forced completely into said slot, and a member in the lock unit to move the pawl from its coin accepting position to a coin releasing position when said lock unit is moved to a locked position.

2. In a lock box assembly, a lock box having an access door and a door jamb, a key-operated lock unit mounted on the jamb, a door-locking latch mechanism mounted on the jamb and including a latch bolt, a co-acting latch plate on the door, an elongated portion of said latch bolt being slidably supported on the jamb and operatively connected with said lock unit for actuation by the lock unit, a pawl pivoted on the jamb and in one position engaging said latch bolt to prevent the latch bolt from moving into latch plate engaging position, said door jamb having a coin slot leading to said pawl, said pawl being adjacent said door jamb slot and being positively shifted from said one position to a coin-accepting and latch bolt releasing position by a coin forced completely into said slot which move-

ment releases said latch bolt for gravity movement towards a latch plate engaging position, said latch bolt having a coin slot extending therethrough, and means for covering said coin slot in said latch bolt after the gravity movement of said latch bolt.

3. In a lock box assembly, a lock box having an access door and a door jamb, a key-operated lock unit mounted on the jamb and free for limited arcuate movement, a door-locking latch mechanism mounted on the jamb and including a latch bolt, a co-acting latch plate on the door, an elongated portion of said latch bolt being slidably supported on the jamb and operatively connected with said lock unit for actuation by the lock unit, a pawl pivoted on the jamb and in one position engaging said elongated portion to prevent the latch bolt from moving into latch plate engaging position, said door jamb having a coin slot leading to said pawl to allow an inserted coin to shift said pawl from said one position to a coin-accepting and latch bolt releasing position at which time gravity moves said latch bolt towards latch plate engaging position, and a member in the lock unit engaging said latch bolt to limit the gravity movement thereof and for moving said latch bolt completely into latch plate engaging position upon movement of said lock unit to locked position.

4. A lock box assembly as in claim 3 wherein said lock unit has an additional member operatively associated therewith for engaging said pawl to move it to a coin releasing position and retaining it in such position as the said lock unit is moved to and retained in locked position.

5. In a lock box assembly, a lock box having an access door and a door jamb, a key-operated lock unit mounted on the jamb, a door-locking latch mechanism mounted on the jamb and including a latch bolt, a co-acting latch plate on the door, the latch bolt being slidably supported on the jamb and operatively connected with the lock unit for actuation by the lock unit, the lock unit including a member engaging the latch bolt for raising the latch bolt to an unlocked position and permitting limited movement of the latch bolt towards its latch plate engaging position

40 when the lock unit is moved to unlocked position, a pawl pivoted on the jamb and in unlocked position engaging the latch bolt to prevent the latch bolt from moving towards latch plate engaging position, the door jamb and the latch bolt each having a coin slot therein which slots are aligned in the unlocked position of the latch mechanism and lead to the pawl, the pawl being positioned sufficiently close to the latch bolt at the slot therein to be positively moved from engagement with the latch bolt by a coin forced through the slots and to be moved from said unlocked position to a coin-accepting and latch bolt releasing position thereby, and a member in the lock nut to move the latch bolt and the pawl from the coin-accepting position towards a coin-releasing position after a coin has been inserted through the slots.
